UNITED STATES PATENT OFFICE.

CHARLES E. NAPP, OF WINTER HAVEN, FLORIDA, ASSIGNOR TO S. CHARLES HIRSCHBERG, OF NEW YORK, N. Y.

TELEPHONE DIRECTORY AND CALENDAR.

Application filed April 26, 1927. Serial No. 186,668.

This invention relates to an improved telephone directory and calendar for use on a desk.

The object of the invention is to provide an improved combined desk telephone directory and calendar of simple, inexpensive construction providing for the convenient use of both the index and calendar while at the same time affording a compact structure requiring little desk space and that can be easily packed and shipped.

A further object of the invention is to provide in a simple way in a device of the character referred to, means for holding a memorandum pad and also a drawer for stamps and other small articles, compactly arranged for ready access and use with the other parts.

The invention, with other objects and advantages thereof, and the particular construction, combination and arrangement of parts comprising the same, will be understood from the hereinafter contained detailed description, when considered in connection with the accompanying drawings, forming part hereof and illustrating one embodiment of the invention.

In the drawings:

Figure 1 is a side elevation of a combined telephone directory and calendar device constructed in accordance with the present invention.

Fig. 2 is a rear end elevation.

Fig. 3 is a transverse section.

Fig. 3^a is a detailed view, on an enlarged scale, of a portion of the stand and drawer.

Fig. 4 is a longitudinal vertical section.

Fig. 5 is a top plan view of the device, the upper frame being shown in closed telescoping relationship with the stand and without the calendar leaves.

Fig. 6 is a top plan view with the upper frame in open position to one side of the stand, and with the drawer partly open.

Fig. 6^a is a transverse section on the line 6^a—6^a of Figure 1.

The invention comprehends a combined telephone directory and calendar embodying the advantages and novel features indicated, and the specific embodiment thereof herein illustrated includes a base or stand having a flat top to support directory leaves or the like and provided with holding means thereon for the same, and an upper frame of general inverted U-shaped form bridging the stand from front to rear with its top part spaced

clear of the top of the stand and mounted thereon to slide laterally thereof for adjustment in closed telescoping relationship therewith and to an open position at one side of the stand, the top of the frame being adapted to support calendar leaves or the like, a compact construction being thus afforded which at the same time provides for ready access and use of both the calendar and directory leaves or the like. The invention further contemplates a construction of this character in which the stand has a drawer arranged to slide within the same from one side thereof, and also in which the top of the stand is adapted to support thereon separate from the directory leaves and in a position convenient for writing thereon, a memorandum pad.

While a preferred embodiment of the invention is illustrated in the drawings, it will of course be understood that minor changes and modifications may be made in the particular construction shown, and the invention embodied in other forms as will appeal to those skilled in the art and falling within the scope of the appended claims without departing from the spirit of the invention.

Referring to a detail description of the particular embodiment of the invention illustrated in the drawings, A designates a stand of general inverted U-shaped construction formed from a continuous piece of relatively light sheet metal, the same comprising an elongated top part 1, and front and rear leg portions 2—3, the legs preferably as shown varying in length so that the top 1 extends at an inclination. The legs 2—3, at their lower ends are flanged to provide feet 4—5, which are shown provided with pads 6 of felt or other suitable material. The top is adapted to support a memorandum pad 7 and a series of telephone directory leaves 8, the memorandum pad 7 being arranged at the forward part of the top 1, and the series of directory leaves 8 disposed rearwardly thereof, said leaves having index tabs 8^a extending to one side of the top. 9 designates hooks struck up from the metal of the top 1 for holding the memorandum pad 7, and 10 are temporary binders or fingers for the index leaves 8. The loops or fingers 10 may be of any suitable construction, the same being shown conveniently formed by portions struck out and bent back from the top 1, the top being provided with slots 11 to receive

the free end portions 10^a of said loops, the loops being sufficiently flexible to provide for bending the same to enter their free end portions 10^a into the slots 11 of the top 1 and to withdraw the same therefrom.

B designates a frame of general inverted U-shaped form having a top part 12, and front and rear sides 13—14. The frame B is disposed longitudinally of the stand A, bridging the same, as shown, with its top part 12 spaced above the top 1 of the stand clear of the temporary binder loops 10, and is mounted on the stand A to slide laterally thereof so that the same may be adjusted to occupy a closed telescoping relationship with the stand A, as illustrated in Figure 5 of the drawings, or opened out from over the directory leaves 8 and memorandum pad 7 to one side of the stand as shown in Figure 6. The frame B, which is preferably, as shown, formed of relatively light sheet metal similar to the stand A, has at the lower ends of its sides 13—14 transverse inwardly extending flanges 15 slidably engaging transverse guide channels 16 on the supporting legs 2—3 of the stand, said leg portions being provided with transverse inwardly extending U-shaped bends forming said guide channels. The sides 13—14 of the frame B are provided at either side marginal portion thereof with inwardly bent portions 17 that cooperate with outwardly projecting portions 18 on the leg portions 2—3 of the stand A at one side thereof and near the top to limit the lateral sliding movement of the frame B to open and closed positions, the stop portions 17 at one side marginal portion of the sides 13—14 of the frame B being spaced from the adjacent ends of the guide flanges 15 sufficiently to permit said stop portions to be positioned back of the stop portions 18 on the legs of the stand prior to engaging the guide flanges 15 of the frame B with the guide channels 16 of the stand in assembling the parts. The frame B is adapted to support calendar leaves 19 so that the same may be turned back or reversed in the usual way with pad calendars, the frame having binder fingers or loops 20 on which the calendar leaves 19 are strung, said binder loops or fingers being shown constructed similar to the binder loops 10 on the stand A, by portions struck out and bent back from the top 12, which is provided with slots 21 to receive the free end portions 20^a of said binder fingers or loops.

The frame B has at its rear end a loop 22 to hold a pencil or pen, and below said loop a filing hook 23, said loop and filing hook being formed by portions struck up from the top 12 and leg 13, as shown.

The stand is provided with a drawer 24 for stamps or other small articles, the drawer being arranged to slide within the stand from one side thereof, the upper wall 16^a of the guide channels 16 on the legs 2—3, form-

ing supporting slides for said drawer. The legs 2—3 of the stand A at one side are provided with inwardly bent portions 25 forming stops to limit the inward movement of the drawer, and the top of the stand A has a depending portion 26 struck therefrom intermediate its ends and near one side edge to limit the outward movement of the drawer 24, the arrangement of the stop portion 26 being such as to permit the removal of the drawer 24 from or the insertion of the same within the frame when tilted as illustrated in dotted lines in Figure 3^a of the drawings.

24^a designates a tray fitted within the drawer 24 and dividing the same into three compartments a, b, c. The drawer 24 is preferably formed of metal and the tray 24^a of celluloid, but these parts may be constructed of any other material suitable for the purpose.

It will be noted that the special construction and arrangement of parts hereinbefore described, affords a combined telephone directory and calendar of a simple efficient nature that can be manufactured at low cost, and the structure afforded being compact, requiring little space on the desk, while at the same time providing for the convenient access to and use of the calendar sheets and the telephone directory sheets and memorandum pad.

What I claim is:

1. A device of the class described including a stand having a flat top to support index leaves or the like and provided with holding means thereon for the same, and frame of general inverted U-shaped form mounted to slide laterally of the stand for adjustment in closed telescoping relationship therewith and to a position from closed telescoping relationship therewith to one side thereof, the top of said frame being adapted to support calendar leaves or the like and having holding means thereon for the same.

2. A device of the class described including a stand having a flat top to support index leaves or the like and provided with holding means thereon for the same, and a frame of general inverted U-shaped form mounted to slide laterally of the stand for adjustment in closed telescoping relationship therewith and to a position from closed telescoping relationship therewith to one side thereof, the top of said frame being adapted to support calendar leaves or the like and having holding means thereon for the same, said stand and frame having cooperating portions limiting the lateral movement of the frame to open and closed positions relatively to the stand.

3. A device of the class described including a stand having a flat top to support index leaves or the like and provided with holding means thereon for the same, and said stand having a drawer slideable within the same from one side thereof, and an upper frame of general inverted U-shaped form bridging

- the top of the stand from front to rear and mounted on the stand to slide laterally thereof for adjustment in closed telescoping relationship therewith and to a position from over the top of the stand to one side thereof, the top of said frame being adapted to support calendar leaves or the like and having holding means thereon for the same.
4. A device of the class described including a stand having an elongated flat top adapted to support a memorandum pad on a forward part thereof, and to support a series of index leaves on the same to the rear of said memorandum pad, temporary binder loops on the top at the rear thereof for the index leaves, means on the top at the forward part thereof for detachably holding the memorandum pad thereon, and an upper longitudinally extending frame of general inverted U-shaped form mounted on the stand to slide laterally thereof for adjustment in closed telescoping relationship therewith and to a position to one side thereof, the top of said frame being adapted to support calendar leaves, and temporary binder loops on the top of the frame for said calendar leaves.
5. A device of the class described including a stand of general inverted U-shaped form having a top adapted to support index leaves or the like and provided with holding means thereon for the same, and a frame of general inverted U-shaped form adapted to telescope with said stand, transverse interengaging guide portions on the sides of the stand and frame supporting the frame on the stand with its top disposed above the top of the stand to slide laterally of the stand for adjustment in closed telescoping relationship with the stand and from said position to one side of the stand, the top of the frame being adapted to support calendar leaves or the like and having holding means thereon for the same.
6. A device of the class described including a stand having an elongated flat top adapted to support index leaves or the like and having holding means thereon for the same, and said stand having transverse guideways on the front and rear sides thereof, and an upper frame of general inverted U-shaped form fitting over the stand lengthwise thereof and supported on the stand with its top part above the top of the stand to slide laterally of the stand to closed telescoping relationship therewith and to a position to one side of the stand, the frame having transverse guide members engaging the guideways of the stand, the top of the frame being adapted to support calendar leaves or the like and having holding means thereon for the same.
7. A device of the class described including a stand of general inverted U-shaped form constructed of sheet-metal and comprising an elongated top supporting-plate portion and front and rear supporting-leg portions, the top plate portion being adapted to support index leaves or the like and having temporary binder loops thereon for the same, and an upper sheet metal frame of general inverted U-shaped form bridging the stand from front to rear and mounted thereon to slide laterally thereof for adjustment in closed telescoping relationship with the stand and to a position to one side thereof, the top of the frame being adapted to support calendar leaves or the like and having temporary binder loops thereon for the same, the front and rear leg portions of the stand having transverse bends forming guide channels, and the sides of the frame having transverse flanges at their lower ends slidably engaging the guide channels of the stand.
8. A device of the class described including a stand of general inverted U-shaped form constructed of sheet-metal and comprising an elongated top supporting-plate and front and rear supporting-legs, and a frame of general inverted U-shaped form and mounted to slide laterally thereof for adjustment in closed telescoping relationship with the stand and to a position to one side of the stand, the supporting-leg portions of the stand having transverse bends to provide guide channels, and the sides of the frame having flanges at their lower ends engaging said guide channels.
9. A device of the class described including a stand of general inverted U-shaped form constructed of sheet-metal and comprising an elongated top supporting-plate and front and rear supporting-legs, and a frame of general inverted U-shaped form mounted to slide laterally thereof for adjustment in closed telescoping relationship with the stand and to a position to one side of the stand, the supporting-leg portions of the stand having transverse bends to provide guide channels, and the sides of the frame having flanges at their lower ends engaging said guide channels.
10. A device of the class described including a stand of general inverted U-shaped form constructed of sheet-metal and comprising an elongated top supporting-plate and front and rear supporting-legs, a frame of general inverted U-shaped form bridging the stand from front to rear and mounted thereon to slide laterally thereof for adjustment in closed telescoping relationship with the stand and to a position at one side of the stand, the supporting-leg portions of the stand having substantially U-shaped transverse inwardly extending bends providing guide channels, the sides of the frame having inwardly extending flanges at their lower ends engaging said guide channels, and a

drawer supported on said guide channel bends of the legs of the stand to slide laterally thereof.

11. A device of the class described including a stand of general inverted U-shaped form constructed of sheet-metal and comprising an elongated top supporting-plate and front and rear supporting-legs, a frame of general inverted U-shaped form bridging the stand from front to rear and mounted thereon to slide laterally thereof for adjustment in closed telescoping relationship with the stand and to a position at one side of the stand, the supporting-leg portions of the stand having substantially U-shaped transverse inwardly extending bends providing guide channels, and the sides of the frame having inwardly extending flanges at their lower ends engaging said guide channels, a drawer supported on said guide channel bends of the legs of the stand to slide laterally thereof, and inwardly bent portions on the supporting legs of the stand at one side thereof forming stops to limit the inward movement of the drawer within the stand.

12. A device of the class described including a stand of general inverted U-shaped form constructed of sheet-metal and comprising an elongated top supporting-plate and front and rear supporting-legs, a frame of general inverted U-shaped form bridging the stand from front to rear and mounted thereon to slide laterally thereof for adjustment in closed telescoping relationship with the stand and to a position at one side of the stand, the supporting-leg portions of the stand having substantially U-shaped transverse inwardly extending bends providing guide channels, the sides of the frame having inwardly extending flanges at their lower ends engaging said guide channels, a drawer supported on said guide channel bends of the legs of the stand to slide laterally thereof, and a downwardly extending portion struck from the top plate of the stand intermediate the ends and

near a side marginal portion thereof to limit the outward movement of the drawer.

13. A device of the class described including a stand of general inverted U-shaped form constructed of sheet-metal and comprising an elongated top supporting-plate portion and front and rear supporting-leg portions, and an upper sheet metal frame of general inverted U-shaped form bridging the stand from front to rear with its top spaced above the top of the stand to slide laterally of the stand for adjustment in closed telescoping relationship with the stand and to a position to one side thereof, the front and rear leg portions of the stand having transverse bends forming guide channels, and the sides of the frame having transverse flanges at their lower ends slidably engaging the guide channels of the stand, and the rear leg of said frame having a portion struck outwardly therefrom providing a filing hook.

14. A device of the class described including a stand of general inverted U-shaped form constructed of sheet-metal and comprising an elongated top supporting-plate portion and front and rear supporting-leg portions, and an upper sheet-metal frame of general inverted U-shaped form bridging the stand from front to rear with its top spaced above the top of the stand to slide laterally of the stand for adjustment in closed telescoping relationship with the stand and to a position to one side thereof, the front and rear leg portions of the stand having transverse bends forming guide channels, and the sides of the frame having transverse flanges at their lower ends slidably engaging the guide channels of the frame, and the top of said stand having a portion struck therefrom at its rear end, said portion being bent rearwardly in a curve to provide a clasp for a pencil or the like.

In testimony whereof I hereunto affix my signature.

CHARLES E. NAPP.
